UNITED STATES PATENT OFFICE.

CHARLES WILLIAM MITCHELL, OF BROOKLYN, NEW YORK, ASSIGNOR OF ONE-HALF
TO CHARLES W. LANSING, OF NEW YORK, N. Y.

PIPE-STRAP.

1,087,036.

Specification of Letters Patent.

Patented Feb. 10, 1914.

Application filed August 7, 1912. Serial No. 713,868.

To all whom it may concern:

Be it known that I, CHARLES W. MITCHELL, a citizen of the United States, residing at Brooklyn, in the county of Kings and State 5 of New York, have invented new and useful Improvements in Pipe-Straps, of which the following is a specification.

The invention relates to pipe hangers, and more particularly to the class of pipe straps.

10 The primary object of the invention is the provision of a strap in which a pipe can be conveniently fastened and supported from a toggle bolt or other fastener mounted within a wall or ceiling, the strap being constructed 15 to conceal the breaking of the plaster or other cementitious covering of the wall or ceiling.

Another object of the invention is the provision of a pipe strap in which the use of 20 screws or other fasteners is avoided, thereby enabling the pipe strap to be fastened about a pipe in a reliable and efficient manner, and also which will permit the hanging of the same upon a wall or ceiling without requiring 25 the use of a number of screws or bolt members.

A further object of the invention is the provision of a pipe strap which is simple in construction, and inexpensive in manufacture.

With these and other objects in view the invention consists in the construction, combination and arrangement of parts as will be hereinafter more fully described, illustrated in the accompanying drawings, and 35 pointed out in the claim hereunto appended.

In the drawings: Figure 1 is a side elevation of a pipe strap constructed in accordance with the invention, the same being 40 shown hung from a ceiling and supporting a pipe. Fig. 2 is a sectional view on the line 2—2 of Fig. 1. Fig. 3 is a plan view of the strap prior to the bending thereof. Fig. 4 is a similar view of a modified form 45 of pipe strap. Fig. 5 is a perspective view of a modification showing the same fastened.

Similar reference characters indicate corresponding parts throughout the several views in the drawings.

50 Referring to the drawings by numerals, 5 designates a portion of a ceiling, the same being provided with the usual hole 6 through

which is passed the toggle bolt 7, the latter being anchored in the ceiling 5 as usual, and to this bolt is connected the pipe strap presently described.

55 The pipe strap comprises a band or sleeve 8 preferably constructed from soft steel, although it may be made from galvanized sheet iron or any other material desired, and 60 is adapted to be bent about a pipe 9 adapted to be supported therein. The band 8 near one end is formed with spaced slots 10, while struck up from the said band 8 near the opposite end thereof are outwardly extending bendable tongues 11, the same being designed 65 to pass through the slots 10 and subsequently folded or bent inwardly and upwardly against the band 8 for securing the ends thereof together and thereby fastening 70 the strap about the pipe. The band 8 is formed with an opening 12 through which is passed the headed end 13 of the toggle bolt 7, whereby the strap will be supported therefrom. The band 9 is trained through suitable openings 14 formed in a canopy plate 15, which is also engaged with the headed end 13 of the toggle bolt 7 and is designed 75 to overlie the holes 6 in the ceiling 5 for concealing the said hole therein.

80 In Figs. 4 and 5 there is shown a slight modification of pipe strap wherein the band 16 is formed near one end with notches 17 opening through the side edges thereof while formed at the opposite end of the band 16 85 are laterally extending bendable tongues 18, the same being designed to be folded inwardly and downwardly within the notches 17 for the fastening of the ends of the band 16 together for embracing a pipe. This 90 band 16 is mounted upon the headed end of the toggle bolt heretofore described in a similar manner with respect to the band 8 previously described.

95 From the foregoing description taken in connection with the accompanying drawings, it is thought that the construction and operation of the invention will be clearly understood, and therefore, a more extended explanation has been omitted.

100 The canopy plate 15 in addition to concealing the breaking of the plaster or other cementitious covering of the wall or ceiling also supports the band or strap in such a

manner as to prevent the edges of the strap from sagging away from the wall or ceiling.

What is claimed is:—

The combination with a band adapted to 5 embrace a pipe, of a plate engaged with the band, a threaded bolt passed through the plate, a collar adjustably engaging the threaded bolt and having opposed pivot

lugs, and a latch bar swingingly supported by said pivot lugs.

In testimony whereof I affix my signature in presence of two witnesses.

CHARLES WILLIAM MITCHELL.
